UNITED STATES PATENT OFFICE.

ARTHUR J. FIX, OF BUFFALO, NEW YORK.

BLADE-SHARPENING MACHINE.

Application filed February 26, 1921. Serial No. 447,909.

This invention relates to machines for sharpening or stropping razor and other blades and more particularly to machines for sharpening or stropping safety razor 5 blades.

The objects of the invention are to provide an efficient machine of relatively simple and inexpensive construction and few parts; also to provide improved blade-holding 10 means for such machines; and also to provide improved means for alining and setting the blades to be sharpened in proper sharpening position. Further objects are to improve the construction of razor stropping 15 and sharpening machines in the other respects hereinafter set forth and claimed.

In the drawings:—

Fig. 1 is a side elevation of a machine embodying my invention, the blade holder being removed.

Fig. 2 is a top plan view thereof.

Fig. 3 is an end elevation thereof.

Fig. 4 is a fragmentary sectional elevation thereof on an enlarged scale.

Fig. 5 is a cross sectional view of the improved blade holder.

Fig. 6 is an elevation of the blade holder and blade positioning gage for the holder.

Fig. 7 is a transverse section of the blade positioning gage.

Fig. 8 is a sectional elevation showing one of the pair of stropping or sharpening rolls.

Fig. 9 is a fragmentary transverse section of the blade holder and the two stropping or sharpening rolls.

Fig. 10 is an elevation of the blade holder.

Fig. 11 is a fragmentary sectional view showing the pivotal connection between the parts of the blade holder.

Fig. 12 is a fragmentary section of another connection between the parts of the blade holder.

A designates the base of the machine and B and C designate two sharpening rolls which may be of any desired construction. In the preferred form illustrated, the rolls are of the type provided with helically wound, leather strips as D, the strip on one roll, as illustrated in Fig. 2 of the drawings, entering between the convolutions of the strip on the adjacent roll. The rolls B and C are mounted on suitable shafts E and F and are driven in opposite directions

through means of the intermeshing gears G 55 and H mounted at the ends of the respective rolls B and C. One of the shafts E is driven by a drive shaft I driven from a motor or other prime mover (not shown).

The invention includes a blade holder and holder-supporting means whereby blades may be held in sharpening positions between the rolls or out of such positions. In the preferred embodiment illustrated, 15 designates a pair of movable posts slidably mounted 60 to raise and lower relatively to the sharpening rolls and adapted to support a blade holder 16. Suitable connections may be provided between the posts and the blade holder, in the preferred form illustrated, the upper end of each post being provided with a recess 17 in which an end of the blade holder is adapted to rest. The invention includes suitable means for moving the holder-supporting posts 15 to and from positions 70 wherein they will permit the blades in the holder to contact with the rolls for sharpening. In the preferred embodiment these means comprise a rack or plurality of notches 18 provided on the posts 15 adjacent 75 their lower ends, which racks are engaged by pinions 19 carried by a shaft 20 journaled in the base of the machine. 21 designates a handle for turning the shaft 20.

It has been found desirable to normally maintain the blade holder in a position wherein blades held in the holder will be out of sharpening contact with the rolls and to provide means normally for tending to cause the blade holder to assume such 80 position. With this purpose in view, resilient means have been provided for normally urging the blade holder to hold the blades in an inoperative or out of sharpening position and the invention also includes means for releasably locking or securing the blade-holding device in sharpening position. In the preferred form of the invention illustrated, 22 designates a spring connected at one end to the base of the machine and at the other end to pinion 19 and acting to turn the pinion so as to resiliently maintain the post 15 in its upper position, as indicated in dotted lines in Fig. 4, wherein blades held by the blade-holding device 85 will be out of sharpening engagement with the rolls, and 23 designates a nut threaded on an end 24 of the shaft 20, which nut 90

100

105

2
serves when tightened, to prevent turning movement or rocking of the shaft under actuation of spring 22 and permits of the blade-holding device being releasably held 5 in blade-sharpening position.

The blade holder is constructed to receive and hold different types of blades and is provided with readily releasable clamping means for firmly securing the blades 10 while they are being sharpened. The preferred embodiment of the blade holder is constructed as follows: The blade holder 16 comprises a pair of clamping members 15 and 26 which are provided with blade-gripping flanges or fingers 27 and 28 respectively. As illustrated in Fig. 5, these clamping members are provided with internal recesses as at 29 to receive a thickened edge of certain types of safety razor 15 blades. The clamping members are preferably pivoted together by means of a plurality of pins 30, each pin having an enlarged head 31 which bears against the outer side of one clamping member, and 20 extending through suitable holes in the members and providing on the outer side of the other clamping member a boss 32, 33 designates a cam shaft or rod journaled in bosses 32 and extending substantially 25 lengthwise of the blade holder and 34 designates cams or eccentrics mounted at intervals on shaft 33. The cam rod 33 has a lever or handle 35 and the other clamping member is provided with a lever or handle 36 extending adjacent handle 35 and the eccentrics 34 are so positioned relatively to the handles that when the handles are closed as shown in Fig. 9, the eccentrics 34 will 30 bear upon the one clamping member and force it towards the other clamping member. It follows that when the handles are pulled apart as illustrated in Fig. 5, the eccentrics will be moved and allow the clamping members to move apart so as to 35 release the blades from the holder. 37 designates a pair of leaf springs interposed between the clamping members for forcing those members apart when the handles of the blade holder are opened. Springs 37 40 may be mounted in any suitable manner, in the form of the invention illustrated, one of the clamping members being recessed as at 38, providing a slot in which the ends of the spring seat and are prevented from turning, and 39 designates a pin or stud secured to one of the clamping members and extending through a hole in the other clamping member when the holder is assembled. 45 It is necessary, in order to secure proper stropping and sharpening of the blades, that the blades be accurately aligned and held to project a certain distance from the holder. Therefore, with a view to securing a quick and accurate alignment and po-

sitioning of the blades in the holder, my invention includes the association with the sharpening machine, of a gage and blade aliner which automatically cooperates with the holder when the holder and blades are 50 placed thereon, to properly position the blades. Referring to Figs. 6 and 7, 40 designates the blade gage and aliner which comprises a blade edge-engaging and alining surface 41 which is adapted to engage 55 and properly aline the edges of the blades to be sharpened, and 42 designates a pair of supporting legs or members for holding the blade holder a proper distance from the blade alining surface 41. In the preferred form illustrated, the blade-alining and positioning device is constructed in the form of an open frame or box, the supports or legs 42 being provided with notches 43 to receive the ends of the blade 60 holder, the legs 42 being connected by means of a back plate 44 and by the flat blade-alining surface 41 which constitutes the bottom of the box.

In the operation of the machine, when it 65 is desired to place blades in the blade holder, the handles of the holder may be pulled apart and the blades readily inserted between the clamping parts, and at this time no attention need be paid to effect any 70 alinement or adjustment of the blades in the holder. The blade holder is then placed in the gage and alining device 40, the handles of the holder being held slightly 75 out of closed position to allow the blades to move in the holder, the ends of the blade holder resting upon the supporting legs 42 of the gage. The edges of the blades which are to be sharpened will automatically aline and level themselves upon the 80 surface 41 of the device and the ends of the blade holder being in contact with the legs 42 of the alining device, indicate and insure that the blades are in proper position for most effective stropping and sharpening. The handles are then closed, the blade holder removed from the gage and placed upon the supporting posts 15, the nut 23 on shaft 20 being loosened so that 85 the shaft may be turned. While the rolls B and C are being driven, the handle 21 is turned to lower the movable posts 15 and permit the blades to move into sharpening contact between the rolls. When the blades have been properly positioned between the rolls, the nut 23 may be tightened, whereupon the blades will be effectually held in such position until the stropping or sharpening operation has been completed. When 90 the sharpening operation has been completed, the nut 23 may be loosened, whereupon the blades will be automatically moved upwardly out of engagement with the sharpening rolls and the blade holder and blades may be lifted off of the supporting 95 posts 15.

posts, with no danger of cutting or scarring the stropping or sharpening leather of the rolls in such removal.

The machine, by reason of the fact that it constantly tends to maintain the blade holder and blades out of sharpening position and engagement with the rolls, permits of very rapid removal of the blade holder and blades from the machine, and there is no danger of cutting or scarring the rolls or breaking the blades, and the handle and shaft for moving the blades to sharpening position against the action of the spring permits of that gradual and restrained feeding movement of the blades towards the rolls which is so necessary to effectual operation. At the same time the blades may be most readily secured in stropping or sharpening position by simply turning the nut 23 on shaft 20. The gage and alining device prevents any danger of misalignment of the blades when they are placed in the machine and permits of such alinement being effected in a very short space of time, in fact substantially no longer than is necessary to rapidly set the blade holder on the gage and alining device and remove it from that device.

I claim as my invention:—

30 1. In a machine for sharpening blades, the combination with a pair of sharpening rolls, of a blade holder movable to and from a blade-sharpening position between said rolls, movable holder posts for said blade holder, a rock shaft, connections between said posts and said rock shaft, a spring normally urging said posts to move said holder from blade-sharpening position, and releasable means for preventing movement of said rock shaft to releasably hold said posts with said blade holder in blade-sharpening position.

2. In a machine for sharpening blades, the combination of a pair of sharpening rolls, a blade holder movable to hold blades

in or out of sharpening positions between said rolls and in contact with both of said rolls, endwise movable holder posts for said blade holder, one end of each of said posts being provided with a series of notches, a 50 rock shaft, and members on said rock shaft engaging the notched ends of said posts, whereby actuation of said rock shaft will move said holder posts endwise to move said blade holder to and from blade-sharpening 55 position.

3. In a machine for sharpening blades, the combination of a pair of sharpening rolls, a blade holder movable to hold blades in or out of sharpening positions between 60 said rolls and in contact with both of said rolls, endwise movable holder posts for said blade holder, a rack on one end of each post, a rock shaft, pinions on said rock shaft engaging said racks, whereby actuation of 65 said rock shaft will move said holder posts endwise to move said blade holder to and from blade sharpening position.

4. In a machine for sharpening razor blades, the combination of a base, a pair of sharpening rolls journalled in said base, a blade holder, a pair of holder posts slidably mounted at opposite ends of said rolls, and common means for simultaneously moving said posts to move said blade holder 70 to and from blade-sharpening positions between said rolls.

5. In a machine for sharpening razor blades, the combination of a base, a pair of sharpening rolls journalled in said base, a 80 blade holder, a pair of holder posts slidably mounted at opposite ends of said rolls, common means for simultaneously moving said posts to move said blade holder to and from blade-sharpening positions between 85 said rolls, and means normally maintaining said blade holder out of blade-sharpening position.

ARTHUR J. FIX.
